UNITED STATES PATENT OFFICE.

BENJAMIN L. BROOKS, OF LYNCHBURG, VIRGINIA.

CIGARETTE HOLDER.

Application filed April 13, 1921. Serial No. 460,905.

To all whom it may concern:

Be it known that I, BENJAMIN L. BROOKS, a citizen of the United States, and a resident of Lynchburg, in the county of Campbell and State of Virginia, have invented certain new and useful Improvements in Cigarette Holders, of which the following is a specification.

My invention relates to cigar or cigarette holders and the purpose of my invention is the provision of a cigarette holder having a stem which is movable to effect the ejection of the cigarette stump from the holder and to operate gripping means for gripping the cigarette when in normal position so that it will be securely retained within the holder, and for releasing the same when occupying ejecting position to allow the ejection of the stump.

10 I will describe two forms of cigarette holders and various forms of holder bodies and gripping devices, all embodying my invention, and will then point out the novel features thereof in claims.

20 In the accompanying drawings:

Figure 1 is a view showing in perspective one form of cigarette holder embodying my invention.

Figure 2 is a view showing in longitudinal section the holder shown in Figure 1 with the stem in ejecting position.

Figure 3 is a view similar to Figure 2 with the stem in non-ejecting position.

Figure 4 is a detailed perspective view of the gripping device shown in the preceding views.

Figure 5 is a longitudinal sectional view of another form of cigarette holder embodying my invention.

40 Figures 6 and 7 are longitudinal sectional views of modified forms of holder bodies.

Figures 8 to 11 inclusive are perspective views showing modified forms of gripping devices adapted to be used in conjunction with the holders shown in Figures 2, 3 and 5.

Figure 12 is a sectional view taken on the line 12-12 of Figure 11 and showing the manner in which the attaching arm is associated with the stem of the holder.

Figure 13 is a perspective view showing in section another form of gripping device in applied position with respect to a cigarette holder.

Figure 14 is a fragmentary sectional view of another form of holder body.

Similar reference characters refer to similar parts in each of the several views.

Referring specifically to the drawings and particularly to Figures 1, 2 and 3, my invention in its present embodiment comprises a hollow body B formed of any suitable material and made up of two sections 15 and 16 of frusto-conical form and having their confronting ends in screw-threaded engagement with each other as indicated at 17. The outer end of the section 16 is provided with an annular flange or collar 18 which is wholly within the body to provide a cigarette receiving socket of tapered cross section. Movable longitudinally within the body B is a stem designated at S, the stem being formed of any suitable material and having an enlarged portion 19 at a point intermediate its ends which provides a shoulder against which one end of a coiled expansion spring 20 is adapted to bear. As shown in Figure 2, the spring 20 is within the body and in embracing position with respect to the flange 18 so that one end of the same bears against the end of the body while its opposite end engages the enlarged portion 19 thereby serving to normally urge the stem as a whole rearwardly toward the section 15. It will be particularly noted that the diameter of the portion 19 exceeds the diameter of the outer end of the section 15 so that the latter forms an abutment for the portion to limit the rearward movement of the stem under the action of the spring. 85 The stem S carries at its forward end a gripping device which as shown in Figure 4 comprises in the present instance a disc 21 formed axially thereof with an opening which is adapted to coincide with the opening of the stem S. At diametrically opposite points upon the periphery of the disc spring arms 22 are formed carrying at their free ends inwardly bent portions 23. At the rear side of the disc, a screw threaded sleeve 90 or extension 24 is provided which in the applied position of the gripping device of the stem as shown in Figures 2 and 3 threadedly engages the wall of the bore of the stem in such manner that a free smoke passage is 95 provided through the gripping device and into the stem. As shown in Figure 2, the spring arms 22 normally occupy divergent positions, that is when the gripping device as a whole is projected from the socket of the body. In this position of the arms the portions 23 are spaced apart sufficiently to 100 105 110

accommodate a cigarette of the usual diameter and to thereby permit of the insertion of the same into the gripping device in the manner shown in Figure 2.

- 5 In the operation of the cigarette holder just described, the stem S normally occupies a retracted or non-ejecting position wherein its forward end is disposed at the extreme inner end of the cigarette receiving socket, 10 it being understood that the stem occupies this position under the action of the spring 20. In applying a cigarette to the holder, the stem S is projected forwardly from the position shown in Figure 3 to that shown in 15 Figure 2 so as to cause the gripping device to be moved from the socket. In this position of the gripping device the spring arms 22 move to expanded or releasing position so as to permit of the insertion of a cigarette 20 between the arms in the manner shown in Figure 2. After the cigarette has been so positioned, the stem is released thereby allowing the spring 20 to return the stem to non-ejecting position. During this movement the gripping device is moved into the 25 socket of the body and because of the tapered formation of the socket the spring arms are contracted to occupy parallel positions wherein the spurs 23 are imbedded within 30 the cigarette so as to securely retain the cigarette within the socket. When the cigarette has been smoked to a point adjacent the body and it is desired to eject the remaining stump, the stem is again moved forwardly 35 thereby simultaneously moving the gripping device to releasing position and ejecting the stump from the socket.

In the assembling of the stem S and sockets of the body B, it will be understood that 40 the stem is first inserted into the body 16 whereupon the section 15 is then applied so that its outer end will cooperate with the enlarged portion 19 in retaining the stem within the body at all times.

- 45 Referring now to Figure 5 I have here shown another form of cigarette holder embodying my invention in which the body is designated at B', such body being of elongated form and formed integral with a 50 tapered socket 25 which is abruptly tapered at its inner end. Movable longitudinally within the body is a stem S' made up of two sections indicated at 26 and 27 which are threadedly connected to each other at 55 their confronting ends with the section 27 of a greater diameter than the socket 26 to provide a shoulder 27* at a point within the body. The body B' is also provided with a shoulder 28 at a point adjacent the inner 60 end of the socket 25, and a coiled expandable spring 29 surrounds the section 26 and is interposed between the shoulders 27* and 28 so that it normally urges the stem rearwardly of the body. The rearward movement of 65 the stem is defined by a head 30 formed on

the forward end of the section 26 and of frusto-conical form so as to snugly seat in the abruptly tapered end of the socket 25 and to thereby prevent further rearward movement of the stem. The head 30 is provided with a screw threaded bore which is adapted to receive a gripping device of the construction shown in Figure 4, the spring arms 22 being moved to gripping and releasing position by their coaction with the walls of the tapered socket 25. This form of cigarette holder operates in the same manner as that described in connection with the form shown in Figures 2 and 3, it being particularly noted, however, that the construction of the stem S' is such as to permit of the body B' being formed in a single piece and of more attenuated form.

Referring now to Figure 6, I have here shown a modified form of body designated at B² and which is adapted to be used in place of the body B in the first form of cigarette holder. The body B² is formed of a single length of bendable material in the place of sections, the rear end of which is adapted to be turned down to the dotted line position after the stem S has been inserted within the body. The finishing of the body in this manner permits of proper abutment of the enlarged portion 19 of the stem in defining the retracted position of the stem. In Figure 7 another form of body designated at B³ is shown, this body being made up of two sections in the manner similar to the body B in which the confronting ends of the sections are connected by screw threads as indicated at 17* and in such manner that the ends of the sections are flush so as to provide a smooth exterior surface on the body. In Figure 14, a third form of body is shown designated at B⁴. This body is adapted to be made in the same manner as the body B² with the exception that the annular flange or collar 18* is made separately 100 of the body and has a screw threaded connection therewith as indicated at 31. By this construction it will be seen that the collar 18* can be removed from the body to permit of the insertion of the stem S into the body, and that after the stem has been applied the collar is replaced thus forming the cigarette receiving socket.

Referring now to Figures 8 to 11 inclusive, I have here shown various forms of gripping devices adapted to be used in conjunction with the stems S and S' and designed to replace the gripping device shown in Figure 4. The gripping device shown in Figure 8 is identical in construction to the device shown in Figure 4 with the exception that the screw threaded extension 24 is dispensed with and supporting arms 32 provided at diametrically opposed points upon the disc 21. These arms 32 extend rearwardly from the disc 21 and are provided

with suitable openings to receive tacks 33 for securing the arms at diametrically opposite points on the forward end of the stem S or S'. It will be seen that by using a gripping device of this construction the necessity of providing a screw threaded extension 24 and interiorly threading the forward end of the stem S or S', is eliminated. In Figure 9 the gripping device 10 is shown in which arms 32 are outstruck to provide spurs 34 designed to take the place of the tracks 33 of the gripping device shown in Figure 8. In Figure 10 the rear free ends of the arms 32 are tapered 15 and bent inwardly to provide retaining spurs 35 which are adapted to be imbedded within the stem S or S' for securing the gripping device as a unit on the forward end of the stem. In Figure 11 the supporting arms 32 are provided with beveled edges 20 as illustrated to advantage in Figure 12, these arms being adapted to fit in correspondingly shaped grooves formed on the periphery of the stem S or S' and locked 25 within the grooves by outstriking the arms to provide retaining lugs 32a which are imbedded within the stem. The spring arms 22 in the present form of gripping device 30 are outstruck at points adjacent their free ends to provide spurs 36 and are adapted to take the place of the spurs 23.

Referring now to Figure 13 I have here shown a body B of the same construction as the body shown in the first form of my invention 35 in which is slidably mounted a stem S², the forward end of which latter is without the screw threaded interior portion with which the stems S and S' are provided. For gripping the cigarette within the socket, 40 the stem S² is provided with spring arms 37 secured at diametrically opposite points upon the periphery of the stem S² by means

of spurs 38. The forward ends of the arms 37 are provided with inwardly bent spurs 39 which are adapted to be imbedded within 45 the cigarette when the arms are retracted within the socket to occupy contracted or gripping position.

Although I have herein shown and described only two forms of cigarette holders 50 and various forms of holder bodies and gripping devices, it is to be understood that various changes and modifications may be made herein without departing from the spirit of the invention or the spirit and 55 scope of the appended claims.

What I claim is:

1. A cigarette holder comprising a stem, having its intermediate portion formed with a shoulder, one side of which is tapered and 60 gradually merges into a mouth piece, a body mounted on the stem and having its forward end formed with an inwardly and rearwardly directed annular flange to snugly receive a cigarette and cooperating with 65 the adjacent portion of the body in forming an annular chamber, and a spring confined between the forward portion of the body and said shoulder and being received in said annular chamber, said annular body 70 consisting of a pair of threaded sections gradually and uniformly enlarged toward their meeting portions, said shoulder being in the path of travel of the rear section of the body to limit the forward movement of the body.

2. The construction set forth in claim 1, and a holder consisting of a head having an attaching portion connected to the forward end of said stem, said head also being 80 provided with forwardly directed spring arms adapted to engage a cigarette.

BENJAMIN L. BROOKS.
